UNITED STATES PATENT OFFICE.

ERNST EMIL FROZETH, OF MINNEAPOLIS, MINNESOTA.

STRINGED INSTRUMENT.

1,426,852.

Specification of Letters Patent. Patented Aug. 22, 1922.

Application filed April 12, 1921. Serial No. 460,753.

To all whom it may concern:

Be it known that I, ERNST E. FROZETH, a citizen of the United States, residing at Minneapolis, in the county of Hennepin 5 and State of Minnesota, have invented certain new and useful Improvements in Stringed Instruments, of which the following is a specification.

This invention relates to improvements 10 in stringed instruments of the violin type and the main object is to provide a new, efficient and practical means for relieving the hollow sound box of the instrument from the tension of the strings, and thus permitting 15 the sound box to more scientifically and accurately execute its vibratory functions, thus bringing out and properly accenting the correct tonal qualities of the instrument. Further objects will be disclosed in the 20 course of the following specification and are illustrated in the accompanying drawing, in which:

Fig. 1 is a vertical sectional view through the center of a violin embodying my invention.

Fig. 2 is an enlarged detail view of the heel plate 18, or as seen from the left in Fig. 1.

Referring to the drawing by reference 30 characters 3 designates a violin body having a neck piece 5, a finger board 6, strings 7, a bridge 8, and a tail piece 9, all of common and well known construction. In the end 4 of the instrument I drill two holes 10 35 and 11, in the latter of which is inserted a tubular brace 12 which extends through the length of the body. A strong wire or rod 13 extends through the brace 12, and is secured with its head 14 in a hole in the neck piece 5 40 of the instrument. A plug 15 may be inserted in this hole so that it will not be noticeable.

An angular brace 16 is inserted in the hole 10 and engages a notch 17 in the brace 45 16, with its inner end. A heel plate 18 has a socket 19 in its inner side adapted to engage the outer end of the brace 16, and is provided with two notches 20 in which may be secured the flexible loop 21 of the tail 50 piece 9, to the latter of which is secured the strings 7. The lower end of the heel plate 18 is adjustably secured to the rod 13 by any suitable means, a convenient construction being shown, and consisting of a 55 set screw 22 which is rotatably mounted in the plate but threads onto the rod 13 so

that when it is turned the lower end of the heel plate will be adjusted closer to or farther away from the instrument, as desired.

It will thus be seen that with the various 60 parts constructed and properly adjusted as above described, the strain caused by the tautness of the strings 7 will be taken up entirely by the parts 9, 21, 18, 16, 12, 13, 22, 14 and 5, leaving the sound box or body 65 of the instrument free to vibrate as it properly should do.

It is of course understood that the invention as here disclosed is purely illustrative and is not to be taken in a limiting sense. 70 Suitable modifications may be made, provided, however, that such modifications come within the spirit and scope of the appended claims. Having now therefore fully shown and described my invention what I claim to 75 be new and desire to protect by United States Letters Patent is:

1. The combination with a stringed instrument having a hollow sound box and a neck piece secured thereon, of a heel plate 80 at the butt end of the instrument, strings positioned over the face of the instrument and means for securing them to the heel plate, a hollow brace extending longitudinally within the sound box, a rod within 85 the brace, said rod being secured at one end in the neck piece and having its other end terminating in the heel plate, an angular brace bracing the heel plate against the first mentioned brace whereby the plate will 90 be spaced from the sound box.

2. The combination with a stringed instrument having a hollow sound box and a neck piece secured thereon, of a heel plate 95 at the butt end of the instrument, strings positioned over the face of the instrument and means for securing them to the heel plate, a hollow brace extending longitudinally within the sound box, a rod within the brace, said rod being secured at one end 100 in the neck piece and having its other end terminating in the heel plate, means for adjustably securing the rod in the heel plate, and an angular brace bracing the heel plate against the first mentioned brace, whereby 105 the plate will be spaced from the sound box.

3. The combination with a stringed instrument having a hollow sound box and a neck piece secured thereon, of a heel plate 110 at the butt end of the instrument, strings positioned over the face of the instrument and means for securing them to the heel

- plate, a hollow brace having a notch in its rear part extending longitudinally within the sound box, a rod within the brace, said rod being secured at one end in the neck 5 piece and at its other end in the heel plate, an angular brace extending through the butt end of the sound box, said angular brace engaging the heel plate at one end and said brace notch with the other end.
- 10 4. The combination with a stringed instrument having a hollow sound box and a neck piece secured thereon, of a heel plate at the butt end of the instrument, strings positioned over the face of the instrument

and means for anchoring the strings to 15 the heel plate consisting of a tail piece having a loop adapted to be secured in a pair of angular notches in the heel plate; a hollow brace extending longitudinally within the sound box, a rod within the brace, said 20 rod being secured at one end in the neck piece and having its other end terminating in the heel plate, and an angular brace bracing the heel plate against the first mentioned brace, as and for the purpose set 25 forth.

In testimony whereof, I affix my signature.
ERNST EMIL FROZETH.
